UPHOLSTERY OR SHADE TRIMMING.

No. 19,421.

Patented Nov. 12, 1889.

UNITED STATES PATENT OFFICE.

GEORGE S. HENSEL, OF PHILADELPHIA, PENNSYLVANIA, ASSIGNOR TO THE HENSEL COLLADAY COMPANY, OF PENNSYLVANIA.

DESIGN FOR UPHOLSTERY OR SHADE TRIMMINGS.

SPECIFICATION forming part of Design No. 19,421, dated November 12, 1889.

Application filed October 21, 1889. Serial No. 327,717. Term of patent 7 years.

To all whom it may concern:

Be it known that I, GEORGE S. HENSEL, a citizen of the United States, residing in the city and county of Philadelphia, State of Pennsylvania, have invented and produced a new and original Design for Upholstery or Shade Trimmings, of which the following is a specification, reference being had to the accompanying photograph, forming part thereof.

The leading feature of my design for upholstery and shade trimming is a head, a ring depending from said head, and a knotted tassel depending from said ring.

In the photograph, A designates the head of the trimming, having a ring B depending therefrom. C designates knotted tassels which depend from said rings.

What I claim is—

A design for upholstery and shade trimmings, substantially as shown and described.

GEORGE S. HENSEL.
